UNITED STATES PATENT OFFICE

MATTHEW A. ROSENTHAL, OF BROOKLYN, NEW YORK

DESIGN FOR A SODA FOUNTAIN REFRIGERATOR

Application filed March 14, 1932. Serial No. 43,178. Term of patent 14 years.

To all whom it may concern:

Be it known that I, MATTHEW A. ROSENTHAL, a citizen of the United States, resident of Brooklyn, in the county of Kings and State of New York, have invented a new, original, and ornamental Design for a Soda Fountain Refrigerator, of which the following is a specification, reference being had to the ac-

companying drawing, forming part thereof.

Figure 1 is a front view and Figure 2 a side view of the soda fountain refrigerator.

I claim:

The ornamental design for a soda fountain refrigerator, as shown.

MATTHEW A. ROSENTHAL.
